Primary Examiner — Cynthia Ramirez*Assistant Examiner* — Michael A Maharajh(74) *Attorney, Agent, or Firm* — Novoclaims Patent Services LLC; Mei Lin Wong(57) **CLAIM**

The ornamental design for a massage fascia tissue roller, as shown and described.

DESCRIPTION

FIG. 1 is a Front elevational view of a massage fascia tissue roller showing my new design;

FIG. 2 is a Rear elevational view thereof;

FIG. 3 is a Left side view thereof;

FIG. 4 is a Right side view thereof;

FIG. 5 is a Top plan view thereof;

FIG. 6 is a Bottom plan view thereof; and,

FIG. 7 is a perspective view thereof.
